FRANK WARD REILLY, OF CHATTANOOGA, TENNESSEE, AND DELMAR C. SHERMAN, OF CHICAGO, ILLINOIS, ASSIGNEES TO WILLIAMSPORT WIRE ROPE COMPANY, A CORPORATION OF PENNSYLVANIA

AERIAL HAULAGE OR CABLE-WAY MECHANISM

Application filed March 5, 1930. Serial No. 433,278.

Our invention relates to aerial tramways or cableways, and its principal purpose is to provide a new, simplified and greatly improved mechanism or arrangement for the proper control and support of the hoist or fall rope.

To this end the principal feature of the invention in its physical embodiment consists in a rope or cable directed or traveling in a continuous circuit and called for convenience a support or carrier line for the hoist or fall rope. The hoist rope and support rope both pass over at least two double grip sheaves, one located on the head tower and the other on the carriage, so that both ropes will simultaneously drive or be driven by the respective sheaves with the result that in effect the weight of the fall rope between the carriage and the head tower is counterbalanced or, as otherwise stated, any tendency to move either rope or either double grip sheave in either direction is accompanied by an equal tendency to move the other rope in the same direction with the result that slack in the fall rope, greater than any predetermined, necessary or desirable amount, is prevented, and the fall block may be positively lowered with no or a light load, even when the carriage is at the maximum distance from the head tower (or at any intermediate distance).

Without means for supporting the hoist line, when the carriage is at a considerable distance from the head tower the line will sag down between the carriage and the head tower unless there is a considerable load suspended from the fall block hook. Conversely when the fall block is light it will not travel down of its own accord because of the pull in the hoist rope caused by its spanning the distance between the carriage and the head tower.

In accordance with previous practice, in most cableways of any considerable length the hoist line and frequently other lines are supported between the carriage and the head tower by means of small idlers which rest on the track cable and are equipped with small wheels for the support of the hoist line. These idlers or, as usually called, fall rope

carriers, are distributed at intervals as the carriage travels outward from the head tower, by various devices. In one arrangement the separate fall rope carriers are connected together by pieces of chain. When the carrier is adjacent the tail tower the chains are all taut; when the carrier is adjacent the head tower the carriers are brought close together and the chains hang down. This system or arrangement is objectionable because of the chains hanging down into the working area, or swinging and tangling together as the carriage moves out from the head tower. In another arrangement the carriers are distributed by a rope placed above the track cable and fitted with steel buttons of varying sizes spaced at regular intervals; each carrier has an eye of suitable size to engage a particular button and is removed from its attachment to the carriage by contact with this button. In another system the mechanism attached to the carriage and driven by one of the track sheaves mechanically deposits the carriers at intervals. In still another system the carriers are arranged to travel on the track cable and are driven at various speeds by one of the running lines. Thus, one carriage may run at one-quarter, one at one-half and one at three-quarters the speed of the carriage and thus maintain a somewhat regular spacing.

All of the above mentioned arrangements involve a multiplicity of small parts and complicated functions with resulting difficulties in keeping the various parts in working adjustment, increased maintenance cost, and in many cases inefficient service, and are otherwise objectionable for reasons understood by skilled persons.

The invention structure, organized as briefly referred to above, dispenses entirely with separate, spaced or traveling fall rope carriers and mechanism for distributing, spacing or recollecting them, and at the same time eliminates disadvantages of such mechanisms or systems. The continuous support or carrier line running over double sheaves which also carry the fall rope, as above stated, in effect balances the pull on the hoist line caused by the span between the car-

riage and the head tower, and eliminates this resistance to the free downward movement of the fall block. Thus, the pull on the hoist line caused by the span between the carriage 5 and the head tower is resisted by the carrier line and only results in corresponding pull in the carrier line instead of restraining the free movement of the fall block. By the balancing effect also, any sag in the fall rope beyond 10 a desired or predetermined amount is prevented in all positions of the carriage.

Additional important features of the invention include construction or arrangement of the double sheaves to have the same contact or grip on the support line as on the hoist line; or conversely, so that pull on either line is communicated with equal force to the other by the sheaves.

It is practically necessary in cableways 20 and other wire rope drives, in many cases, in order to increase the amount of tractive force transmitted from a wheel to a rope or vice versa, to provide grip mechanism on the wheel or sheave. The common form of grip 25 wheel contains jaws set in recesses around the wheel rim. The radial pressure of the rope acting against the jaws, which are connected in the form of toggles, multiplies the pressure exerted against the rope and has the 30 same effect as increasing the coefficient of friction. The grip wheels employed on an aerial tramway are usually of large diameter, and it is practicable to use such gripping jaws in these large wheels. It is not desirable to 35 employ such large diameter wheels in the carriage and head works of a cableway, and it is difficult or unsatisfactory to employ gripping jaws in wheels of small diameter because it is impracticable to make the jaws narrow 40 enough to form a nearly circular contour, and the jaw type of gripping wheels is also more expensive to manufacture in small diameters, and for other reasons.

While in the broader aspect of the invention 45 any suitable form of gripping wheel, or double grip sheave for positive and equalized traction effect on both the carrier and fall ropes, might be employed, the invention includes as a preferred arrangement 50 double groove or grip wheels of novel and improved character employing a plurality of annular rings instead of grip jaws, and designed to provide ample and equalized 55 traction engagement, as between each of two ropes and the corresponding groove-forming members on the wheel. These double 60 wheels or sheaves conform to several features of design which are of great importance, or essential to proper operation of the present fall rope support arrangement or system. It is important or essential that the groove for the hoist line and the groove for the carrier line be at the same radius from 65 the center of the grip wheel. If variation

should exist in the radius of these two ropes it is evident that one will travel faster and farther than the other. This effect would be continuous in the same direction and would eventually greatly decrease the stress 70 on one of the ropes and greatly increase it on the other.

In the present construction or arrangement of the fall rope support sheaves, as fully explained in the detailed description, provision is made for equal gripping or traction 75 and equal radius at all times of both ropes on the double sheaves, and by means entirely novel and distinct from the grip jaw arrangement.

To sustain or support the hoist line with a constant force, eliminate necessity for adjustment in the length of the carrier line to compensate for stretching, etc., the invention 80 also preferably includes means for applying constant tension to the carrier line. For this purpose the sheave at the tail tower which supports the bend of the carrier line remote from the head tower, is mounted in a movable cradle or slide, and is connected 85 to a counterweight suspended near or within the tail tower. This counterweight places the carrier line under desired uniform or constant tension and thus causes the hoist line to be supported to a uniform degree. 90 It also eliminates the possibility of overstrain in the carrier line due to slackness in the track cable or other causes.

The characteristics and advantages of the invention are further sufficiently explained 100 in connection with the detail description of the accompanying drawings, which show representative embodiments. After considering these examples, skilled persons will understand that many variations may be 105 made without departing from the principles disclosed and we contemplate the employment of any structures that are properly within the scope of the appended claims.

Fig. 1 is a side elevation, largely diagrammatic, of a cableway or aerial haulage system, embodying the invention in one form;

Fig. 2 is a side elevation of the carriage and adjacent parts; and

Fig. 3 is a diagrammatic, perspective view 115 explaining the course or direction of certain of the ropes or lines.

In Fig. 1, 1 is a head tower and 2 the tail tower, supporting the track rope or cable 3, the ends of which are anchored, and the 120 towers are guyed or braced in any known or suitable way. The carriage 4 is supported to travel on the track rope by any known or suitable wheel or truck arrangement such as 5. The carriage supports the fall block 6 through the fall or hoist rope 7. The carriage is traversed between the towers by an outhaul rope or line 8 connected to the carriage at 9, passing over a sheave 10 on the tail tower, under guide pulleys in the car- 125 130

riage, over sheave 12 on the head tower, down through the tower and about sheave or pulley 13 to the traversing or traction drum of the driving mechanism, (not shown), and inhaul 5 rope or line 14 running directly from the carriage to sheave 15 on the head tower then down through the tower and guided as by pulley or sheave 16 to the traction drum. The fall rope may be rigged in the carriage 10 in any known or suitable way. As shown, it is connected to the block 6 at 18, runs over a sheave 19 in the carriage, then around the fall block sheave 20, upward therefrom and over a sheave 21 in the carriage, and then 15 substantially parallel to the other lines, to and over a sheave 22 in the head tower and down through the tower and about a sheave or pulley 23 to the hoisting drum.

As so far described the construction or 20 arrangement of parts may be as usual.

The towers are shown close together in the drawings for illustrative convenience, but actually the distance between the towers may be of the order of 1000 or 1500 or more feet, 25 and the invention is especially advantageous in cases where the tower spacing is relatively great, for reasons that will appear, although of course it is not limited to such cases and may be employed with smaller distance of 30 tower spacing down to any reasonable minimum.

When the distance between towers is relatively great, when the carriage is run out half way or more or close to the tail tower, 35 the weight of the fall rope between the head tower and the carriage is increased correspondingly, and in absence of supporting means, and especially when there is no load or only a light load on the fall hook, the 40 weight of the line is greater than that of the fall block and it will sag and raise the fall block to the carriage; it is impossible also in such cases to lower the block since letting out the fall rope will result only in increasing 45 the length of the depending loop between the head tower and the carriage. To overcome this difficulty the expedients briefly referred to early above have been employed or proposed, such expedients or means consisting principally in the provision of a 50 number of fall rope carriers with means for distributing or spacing them and involving the complications and disadvantages also briefly beforementioned.

55 The invention provides new and improved means for controlling or supporting the fall rope between the carriage and the head tower in such manner that the occurrence of slack in that stretch of the rope is prevented, 60 the differences in weight applied at the fall block are compensated for, and fall rope carriers of types heretofore known and their accompanying disadvantages are eliminated. This improved means for controlling the fall 65 rope may be referred to as a fall rope sup-

port or carrier, by analogy to previously known devices in its general result or function, that is, to support or eliminate undesired sag in the fall line, although in physical organization and operative functions it is 70 entirely different from such previous devices or arrangements, and may therefore be more correctly referred to as fall rope controlling or compensating means, or more specifically, with reference to its principal physical element, a fall rope controlling or compensating line.

This controlling, compensating or supporting line 30 is directed and travels in a continuous circuit between the head and tail towers and through the carriage. Thus, beginning at the head tower, it passes about an idler sheave 31 thereon, up and over a second groove in sheave 22 which also has a groove for the fall rope as above stated; then outward and through a second groove in sheave 21 in the carriage which also has a groove for the fall rope as before stated, then down and under a sheave 32 in the carriage, outward toward the tail tower and about a 90 sheave 33 thereon, then inward toward the head tower, through the carriage (being guided by idler pulleys 34 therein), and so back to the head tower and about idler 31, completing the controlling rope circuit. 95

The pulleys 21 and 22 are above referred to as double groove pulleys each carrying both the fall rope and the controlling or support line. In the broader aspect of the invention the two lines at either the tower or the carriage may pass over independent pulleys or sheaves mounted on the same shaft and connected to rotate together; but in a preferred arrangement for reasons sufficiently stated above, and hereafter, we preferably employ 100 both in the tower and in the carriage a double grip groove sheave of the character disclosed in a companion application, Serial #433,277, filed March 5, 1930, which provides for maintenance of absolutely uniform radius and 105 therefore equal travel of both ropes, and also by simple means provides for powerful gripping of both ropes so that they are simultaneously driven or simultaneously drive the sheave at identical speeds and without slip- 110 page. Each of the sheave structures 21 and 22, supporting both the fall line and the compensating line may therefore in a more limited aspect be considered to be of the form 115 or structure disclosed in said companion application, but since such a sheave structure is capable of other uses, it is not specifically claimed herein except in connection with other features of the present combination. 120

In what is probably the simplest arrangement the stretches of the fall rope and supporting or compensating line between the head tower and carriage are horizontally parallel and are shown approximately so in Fig. 1, but for explanatory purposes the fall 130

line 7 is shown as located slightly above the adjacent stretch of the compensating line 30. Fig. 2 explains better than the small scale showing of Fig. 1, the locations, courses or directions of the various ropes or lines in and adjacent the carriage, and the perspective diagram, Fig. 3, still better explains the locations or arrangements of the fall rope and compensating line and especially those parts 10 of these lines which are in the upper part of the head tower; and extend between the head tower and the carriage, and also parts of the lines located in the carriage and with respect to which Fig. 1 is not so clearly readable 15 on account of its small scale. The sheave structures 21 and 22 are represented diagrammatically in Fig. 3 as each consisting of two sheaves connected to rotate together. This is for the sake of illustrative clearness, since 20 although the two sheave arrangement is feasible, the double grip sheave construction or arrangement as elsewhere described is usually preferable.

While, as above stated, an arrangement in 25 which portions of the supporting or compensating line and of the fall rope between the head tower and carriage are adjacent and horizontally parallel, is one of the simplest and most practical, this is not essential, since 30 the portion of the support or compensating line between the head tower and carriage might be longer than the corresponding portion of the fall rope, and directed in a different course, so long as the supporting line is 35 properly engaged with the double grip sheaves or their equivalents, runs in a continuous circuit and is otherwise arranged to produce the herein described controlling or compensating effect.

40 In operation, when the carriage is at any considerable distance from the head tower, or near the tail tower, as represented in Fig. 1, the weight of the fall rope between the head tower and carriage is greatly increased, 45 and as above stated there is a tendency for it to sag, and with any ordinary, or light load, or no load on the fall block the latter would be pulled up to the carriage. This sagging of the fall rope is however, resisted 50 initially by the compensating line, since assuming the carriage to be held stationary by its traversing lines, the tendency to sag will take effect in a tendency to rotate sheave 21 clockwise, as viewed in Fig. 1; but this rotary impulse applied to the sheave is immediately communicated to the compensating line which thereupon tends to rotate sheave 22 at the head tower in the same direction, and sheave 22 simultaneously applies 55 an equal pull to the fall rope; or in other words, the weight of the fall rope and its tendency to move is substantially compensated and the weight of the fall block even with a light load or no load is sufficient to prevent 60 sagging of the fall line and upward movement of the block. Similarly, under stated conditions, that is, with the carriage well out from the head tower and no load or a light load on the block, if it is desired to lower the block, the fall line is slackened off at the hoisting drum. Neglecting the weight 70 of the fall line downward in the head tower from sheave 22, and the weight of the fall block, there will evidently be an immediate tendency of the rope to sag between sheaves 75 21 and 22 with accompanying rotation of sheave 21 clockwise and sheave 22 counterclockwise; but such rotation is positively prevented by the control line 30, and the fall rope cannot sag between the tower and the carriage to any greater degree than the similar stretch of the control line. The fall block may then be positively lowered so long as its weight is greater than that of the down 80 stretch of the fall rope in the head tower. As otherwise described, the weight of the fall block becomes a positive motive force tending to rotate sheave 21 and thereupon the control line between that sheave and sheave 22 will positively rotate the latter 85 and take up the down stretch of the fall rope at the same rate that it travels between sheave 22 and sheave 21 and over the latter.

90 It will be understood that there may be a normal sag in any or all of the lines or ropes due to their weight when properly tensioned, and in referring to elimination of sag or slack it is only intended to indicate that there is prevention of such sagging beyond a predetermined or normal amount.

95 As sufficiently explained above it is desirable to maintain constant tension on the support or controlling line 30, to compensate for variable stretching of the ropes, to support 100 the hoist line with constant force, to eliminate necessity for adjustment in the length of the compensating line, etc. For these reasons sheave 33, carrying the compensating line at the tail tower, is mounted on a movable support or slide 40 which in the present 105 example is arranged to reciprocate in guides 41. A counterweight 42, the weight of which may be varied or adjusted as desired, is suspended within the tower on a rope 43 connected to slide 40 and guided by sheaves or 110 pulleys 44 and 45, the latter being so located as to provide ample outward travel of the slide and sheave 33 to take up any reasonable amount of slack.

115 The compensating line does not interfere in any way with normal operation of the carriage or fall block. Thus, if the carriage is traversed outward or inward and it is not desired to raise or lower the fall block simultaneously, the sheave 21 will remain stationary relative to the carriage. The fall line and the compensating line will, in effect, run with the carriage in synchronism with the inhaul traction line 14. The compensating 120

line in its entirety operates with the traction line and has additional movement with the fall line when raising or lowering the fall block. Whenever the fall line is slackened off or pulled in to lower or raise the block, the compensating line will travel in the same direction and at the same speed as the fall line.

Figure 1 shows one way, which is the 10 usually preferred way, of reeving the fall rope 7 through the carriage. There is another method in which the end of the fall rope away from the head tower is connected at a fixed point on the tail tower, the rope 15 being rove through the carriage sheaves in a known way, as understood in the art. The present invention will properly cooperate with either mode of reeving the fall rope, to produce the desired results above set forth, 20 as will be understood by skilled persons without further explanation.

We claim:

1. In a cableway or the like, in combination with a track cable, a carriage, carriage 25 traversing means, a hoist rope, extending to and operated from one end of the cableway and load receiving means on the hoist rope, a controlling line movably supported in a continuous circuit and unconnected laterally to the hoist rope which is free throughout to run divergently from the controlling line, and means drivingly interconnecting the controlling line and hoist line whereby the controlling line balances pull on the free stretch 30 of the hoist line, prevents undesired sagging thereof, and effects positive descent of the load receiving means when relatively light or unloaded.

2. In a cableway or the like, in combination with towers, a trackway, a carriage running on the trackway, a hoist rope running from one of the towers to the carriage and a fall block on the hoist rope below the carriage, a hoist rope compensating line supported and guided in a continuous circuit between the towers and adjacent the carriage, the hoist rope and compensating line being free throughout for relative separation in hoisting and lowering of the fall block, and means by which the compensating line is drivingly connected to the hoist rope and counterbalances forces acting on the hoist rope between the carriage and tower, prevents sagging of the fall rope beyond a predetermined amount and permits descent of the fall block when relatively light or unloaded.

3. In a cableway or the like, in combination with towers, a track cable between the 60 towers, a carriage running on the cable, carriage traversing means, a hoist rope running from one of the towers to the carriage and a fall block on the hoist rope below the carriage, a hoist rope compensating line supported and guided in a continuous circuit

between the towers and passing through the carriage, the hoist rope and compensating line being substantially adjacent, parallel, and unconnected to each other from the block to the tower at the operating end of the cable, 70 way, and means by which the compensating line is interconnected with the hoist rope in respect to line or motion and in effect counter-balances forces acting on the hoist rope between the carriages and the tower, prevents 75 sagging of the fall rope beyond a predetermined amount and permits descent of the fall block when relatively light or unloaded and when the carriage is so positioned that the free stretch of the hoist rope is relatively 80 long.

4. An aerial haulage system comprising a head tower, a tail tower, a trackway between the towers, a carriage running on the trackway, a sheave structure in the head tower consisting substantially of a double groove sheave, another substantially similar sheave structure in the carriage, a fall rope running through one groove of each of said sheaves and a fall block on the fall rope below the carriage, a fall rope compensating line running in the other grooves of said sheaves, and additional means supporting the compensating line in a continuous circuit between the towers, whereby forces acting on the fall rope 90 between the head tower and carriage are compensated, sagging is prevented and positive descent of the fall block is effected with light or no load.

5. An aerial haulage system comprising a head tower, a tail tower, a trackway between the towers, a carriage running on the trackway, a sheave structure in the head tower consisting substantially of a double groove sheave, another substantially similar sheave structure in the carriage, a fall rope running through one groove of each of said sheaves and a fall block on the fall rope below the carriage, a fall rope compensating line running in the other grooves of said sheaves, an 100 idler sheave on the tail tower, the compensating line running also about the idler sheave and being directed in a continuous circuit between the towers and through the carriage, whereby forces acting on the fall rope between the head tower and carriage are compensated, sagging is prevented and positive descent of the fall block with light or no load is effected.

6. An aerial haulage system comprising a head tower, a tail tower, a trackway between the towers, a carriage running on the trackway, a double grip groove sheave in the head tower, a double grip groove sheave in the carriage, a fall rope running through the tower and from the tower to the carriage and engaged in one of the grip grooves of each of the said double grip groove sheaves, a fall block on the fall rope below the carriage, an 110 idler sheave in the tail tower, and a fall rope 120

compensating line running through the other grooves of said double grip groove sheaves and over the idler sheave in the tail tower and directed in a continuous circuit between the towers.

7. An aerial haulage system comprising a head tower, a tail tower, a trackway between the towers, a carriage running on the trackway, a double grip groove sheave in the head tower, a double grip groove sheave in the carriage, a fall rope running through the tower and from the tower to the carriage and engaged in one of the grip grooves of each of the said double grip groove sheaves, a fall block on the fall rope below the carriage, an idler sheave in the tail tower, a fall rope compensating line running through the other grooves of said double grip groove sheaves and over the idler sheave in the tail tower and directed in a continuous circuit between the towers, and means for tensioning the compensating line.

8. An aerial haulage system comprising a head tower, a tail tower, a trackway between the towers, a carriage running on the trackway, a double grip groove sheave in the head tower, a double grip groove sheave in the carriage, a fall rope running through the tower and from the tower to the carriage and engaged in one of the grip grooves of each of the said double grip groove sheaves, a fall block on the fall rope below the carriage, an idler sheave in the tail tower, a fall rope compensating line running through the other grooves of said double grip groove sheaves and over the idler sheave in the tail tower and directed in a continuous circuit between the towers, said idler sheave being mounted in a movable support, and means counterweighting the sheave support to tension and take up slack in the compensating line.

9. An aerial haulage system comprising a head tower, a tail tower, a trackway between the towers, a carriage running on the trackway, a double grip groove sheave in the head tower, a double grip groove sheave in the carriage, a fall rope running through the tower and from the tower to the carriage and engaged in one of the grip grooves of each of the said double grip groove sheaves, a fall block on the fall rope below the carriage, an idler sheave in the tail tower, a fall rope compensating line running through the other grooves of said double grip groove sheaves and over the idler sheave in the tail tower and directed in a continuous circuit between the towers, and another compensating line directing pulley in the head tower.

10. A cableway comprising a head tower, a tail tower, a track cable between the towers, a carriage running on the track cable, a sheave structure in the head tower consisting substantially of a double groove sheave, another substantially similar sheave structure in the carriage, a fall rope running through

one groove of each of said sheaves, a fall block on the fall rope below the carriage, and a fall rope compensating or supporting line running in the other grooves of said sheaves, and additional means supporting the compensating line in a continuous circuit between the towers, whereby forces acting on the fall rope between the head tower and carriage are compensated, sagging is prevented and positive descent of the fall block with light or no load is effected.

11. A cableway comprising a head tower, a tail tower, a track cable between the towers, a carriage running on the track cable, a sheave structure in the head tower consisting substantially of a double groove sheave, another substantially similar sheave structure in the carriage, a fall rope running through one groove of each of said sheaves, a fall block on the fall rope below the carriage, and a fall rope compensating line running in the other grooves of said sheaves, an idler sheave on the tail tower, the compensating line running also about the idler sheave and being directed in a continuous circuit between the towers and through the carriage, whereby forces acting on the fall rope between the head tower and carriage are compensated, sagging is prevented and positive descent of the fall block with light or no load is effected.

12. A cableway comprising a head tower, a tail tower, a track cable between the towers, a carriage running on the track cable, a double grip groove sheave in the head tower, a double grip groove sheave in the carriage, a fall rope running up through the tower and from the tower to the carriage and engaged in one of the grip grooves of each of the said double grip groove sheaves, a fall block on the fall rope below the carriage, an idler sheave in the tail tower, and a fall rope compensating line running through the other grooves of said double grip groove sheaves and over the idler sheave in the tail tower and directed in a continuous circuit between the towers.

13. A cableway comprising a head tower, a tail tower, a track cable between the towers, a carriage running on the track cable, a double grip groove sheave in the head tower, a double grip groove sheave in the carriage, a fall rope running up through the tower and from the tower to the carriage and engaged in one of the grip grooves of each of the said double grip groove sheaves, a fall block on the fall rope below the carriage, an idler sheave in the tail tower, a fall rope compensating line running through the other grooves of said double grip groove sheaves and over the idler sheave in the tail tower and directed in a continuous circuit between the towers, said idler sheave being mounted in a movable support, and means counterweighting the

sheave support to tension and take up slack in the compensating line.

14. A cableway comprising a head tower, a tail tower, a track cable between the towers, a carriage running on the track cable, a double grip groove sheave in the head tower, a double grip groove sheave in the carriage, a fall rope running up through the tower and from the tower to the carriage and engaged in one of the grip grooves of each of the said double grip groove sheaves, a fall block on the fall rope below the carriage, an idler sheave in the tail tower, a fall rope compensating line running through the other grooves of said double grip groove sheaves and over the idler sheave in the tail tower and directed in a continuous circuit between the towers, and another compensating line directing sheave in the head tower.
15. A cableway including head and tail towers, a trackway, a carriage running on the trackway, and carriage traversing means, in combination therewith a fall rope running from the head tower to the carriage and a block thereon below the carriage, and fall rope controlling means including as principal essentials a fall rope compensating line directed in a continuous course between the towers and through the carriage, and sheave mechanism in the head tower and in the carriage respectively, each said sheave mechanism consisting substantially of two rope grooves connected to rotate together, the stretches of the fall rope and compensating line between the tower and carriage being engaged respectively in corresponding grooves of the two sheave mechanisms whereby the compensating line and said stretch of the fall rope are interconnected, said stretch of the fall rope is restrained from undesired sagging, and lowering of the fall block is definitely effected when relatively light or unloaded.

16. An aerial haulage system comprising a trackway, a carriage thereon, carriage traversing means, a fall rope extending from one end of the trackway to and through the carriage, a load-support on the fall line below the carriage, a compensating line physically free and independent of the fall rope and movable in a continuous circuit between the ends of the trackway, and rotary connecting means between the fall rope and compensating line near one end of the trackway and in the carriage.
